UNITED STATES PATENT OFFICE.

EDWARD CLARKE, OF DUNKIRK, NEW YORK.

MACHINE FOR DRILLING HOLES IN LENSES.

SPECIFICATION forming part of Letters Patent No. 772,784, dated October 18, 1904.

Application filed April 18, 1904. Serial No. 203,779. (No model.)

To all whom it may concern:

Be it known that I, EDWARD CLARKE, a citizen of the United States, residing at Dunkirk, in the county of Chautauqua and State of New York, have invented certain new and useful Improvements in Machines for Drilling Holes in Lenses; and I do declare the following to be a full, clear, and exact description of the invention, such as will enable others skilled in the art to which it appertains to make and use the same.

My invention is an improved machine for drilling holes in lenses and other articles of glass or similar material; and it consists in the construction, combination, and arrangement of devices hereinafter described and claimed.

This machine is especially adapted for use for drilling holes for screws in lenses, but may be employed for other similar purposes, and I do not desire to limit myself in this particular.

In the accompanying drawings, Figure 1 is a perspective view of a drilling-machine embodying my improvements. Fig. 2 is a detail vertical sectional view of the same. Fig. 3 is a detail top plan view of the same, showing the base and the gage thereon, the standard being shown in cross-section.

The base 1, which is preferably of the form here shown, but which may be of any suitable form and size, has its upper surface 2 plane. At one side of the base is a vertical standard 3, which has an arm 4 at its upper end that projects over the center of the base. At a suitable distance from its upper end the standard has an arm 5, which aligns with the arm 4 and is provided at its outer end with a bearing 6 for a vertical rotating spindle or shaft 7. The latter is provided with a pulley 8, whereby power may be applied thereto from any suitable motor. At the lower end of the spindle or shaft 7 is a suitable socket and a set-screw 9, whereby a suitable drill-point 10 may be detachably and adjustably secured to the lower end of said spindle or shaft. The upper end of the latter operates in an opening in the arm 4, near the outer end thereof, and to the upper end of the said spindle or shaft is swiveled and loosely connected a yoke 11, which comprises a base 12

and a pair of vertical lugs 13. At the outer end of the arm 4 is a bearing 14 for a vertically-adjustable stud 15, which may be set at any desired adjustment by means of a set-screw 16. To the upper end of the said adjusting-stud is pivoted one end of a lever 17, to which the lugs 13 of the yoke 11 are pivoted by means of a pivot-pin 18. Said lever-arm projects rearwardly from the spindle and is provided at its rear end with a suitable handle 19.

In the upper end of the standard is a vertical threaded opening in which is secured the depending stud 20 of an adjustable stop and guide 21, which is provided in its upper end with a vertical guide-slot 22, through which the lever 17 extends. The function of this guide and stop is to guide the lever when the same is moved downwardly and also predetermine the extent of its downward movement and the corresponding downward movement of the spindle or shaft 7, which carries the drill-point. The lens to be drilled is placed on the upper side of the base and is appropriately set thereon by means of a readily adjustable gage 23. Said gage has a curved inner side 24, which corresponds in shape with one side of the lens and is provided with an adjusting-slot 25, which is engaged by a screw 26, that serves to screw the gage on the base at any suitable adjustment. The base is here shown as provided with a center-point 27, which is directly in line with the point of the drill-tool and with a gage-line 28, which intersects the said opening 27 and the axis of the gage.

From the foregoing description, taken in connection with the accompanying drawings, the construction and operation of the invention will be readily understood without requiring a more extended explanation.

Various changes in the form, proportion, and the minor details of construction may be resorted to without departing from the principle or sacrificing any of the advantages of this invention.

Having thus fully described my invention, what I claim as new, and desire to secure by Letters Patent, is—

A drilling-machine of the class described, 100

comprising a base forming a rest for the work, a standard having bearings disposed over the base, a revoluble drill-spindle journaled in the bearings and having means whereby it may be rotated, a lever and a connection between the latter and the drill-spindle to raise and depress the drill-spindle, means to adjust the pivot of said lever, and an adjustable stop for the said lever to predetermine the downward

movement thereof and of the drill-spindle, 10 substantially as described.

In testimony whereof I have hereunto set my hand in presence of two subscribing witnesses.

EDWARD CLARKE.
